RINGING CONTROL ARRANGEMENT FOR
TWO-WAY CARRIER TELEPHONE TERMINALSWalter Brandt, Jersey City, N. J., assignor to
Federal Telephone and Radio Corporation,
New York, N. Y., a corporation of Delaware

Application April 30, 1945, Serial No. 591,068

10 Claims. (Cl. 179—84)

1

This invention relates to ringing control arrangements especially adapted for use in carrier current telephone systems.

A principal object is to provide an improved carrier communication system wherein the frequency or frequencies for control purposes, e. g. ringing control, is within the frequency range of the intelligence signal frequencies, and wherein an improved arrangement is provided for controlling the application of ringing current.

Another object is to provide a carrier signalling system with a two-way terminal having an improved ringing current generator and switching arrangement associated therewith which can be selectively controlled by low frequency ringing currents in one direction and by voice frequency ringing currents in the opposite direction.

A further object is to provide a voice frequency ringing current generator which in one set of signalling conditions acts as a highly selective amplifier discriminator, and as a ringing current generator of voice frequency in another set of conditions.

A feature of the invention relates to an improved two-way carrier telephone terminal for connecting a carrier frequency channel to a trunking line or switchboard, and employing a grid-controlled tube having circuit connections for causing it to act as a regenerative amplifier for controlling the switching-in of a low frequency ringing current, and also responsive to a low frequency ringing signal from the trunk line to convert the amplifier into a ringing-out generator of voice frequency ringing current.

Another feature relates to an improved voice frequency ringing current generator and intelligence signal discriminator, especially adapted for use in a two-way terminal between a carrier frequency channel and a voice frequency line.

A further feature relates to a discriminator for discriminating between voice frequency intelligence signals and voice frequency ringing signals, employing an electron tube with associated circuits whereby the operating characteristics of the tube can be converted from a selective amplifier to a relatively high level voice frequency ringing current generator.

Other features and advantages not particularly set forth are nevertheless inherent in the arrangements forming the subject matter of the invention.

Referring to the single figure of the drawing there is shown by way of example, one typical carrier frequency signalling system wherein the invention can be usefully embodied. It will be

understood that in certain of its aspects the invention is not necessarily limited to voice frequency carrier communication systems, but is capable of application to similar systems whereby discrimination can be effected between control function currents such as ringing currents and intelligence signals.

The drawing shows in somewhat generalized schematic form a two-branch two-way terminal which connects the low frequency or trunking line 1 to the carrier frequency channel 2. When a calling connection is to be extended from the line 1 to the line 2 a low frequency ringing current, e. g. 20 C. P. S., is applied over line 1, thence through the armature 3 and associated back contact of relay 4, windings 5 and 6 of the hybrid coil arrangement 7, through low frequency condenser 8, armature 9 and associated back contact. Connected across condenser 8 in series with another condenser 10, is an alternating current relay 11 which operates in response to the 20 cycle ringing current, and at its armature 12 and associated front contact completes an operating circuit over conductor 13 through the winding of relay 14. Associated with relay 14 is a continuously operating carrier frequency generator tube 15 which may be of any well-known grid-controlled type. Merely for illustration it is shown as a pentode having its control grid coupled through the oscillatory circuit 16, 17 in sustained feedback relation to a tuned oscillatory plate circuit comprising inductance 18 and parallel tuning condensers 19, 20, 21 for tuning the generator sharply to the required carrier frequency.

The carrier generator is coupled through any suitable coupling transformer 22 to any well-known modulator device or network 23. Modulator 23 is arranged to have its input supplied with voice frequency signals representing either intelligence or ringing control, so that there is applied to the band-pass filter 24 a voice frequency modulated carrier which is further amplified in a suitable carrier frequency amplifier 25, and applied through the selective directional filter 26 to the carrier channel 2.

Also associated with relay 14 is a convertible amplifier-to-oscillator tube 27 which, merely for illustration, is shown as of the pentode type. When relay 14 is deenergized the tube 27 acts as a highly selective amplifier having a slight amount of regeneration to increase its selectivity. For this purpose the control grid 28 is returned to the cathode 29 through winding 30 of a voice frequency transformer 31 whose associated winding 32 is connected in the plate return circuit.

Winding 32 is coupled through condenser 33 to an additional feedback transformer whose winding 34 is in the plate circuit of tube 27 and whose associated winding 35 is arranged to be switched into the grid circuit under control of relay 14. Each of the windings 32, 34 is tuned by a respective condenser 36, 37 to the voice frequency used for ringing. In effect the elements 31, 37 constitute a sharply tuned filter for the voice frequency ringing current. Thus tube 27 does not operate as ringing current generator until a sufficient A. C. potential at the ringing frequency is applied to the grid 28.

When relay 14 is operated in response to a ring-out signal from line 1 as above described, the above-mentioned tuned feedback circuit is completed from plate 38 through armature 39 and its associated front contact, to grid 28. Tube 27 therefore generates a relatively high level ringing current of voice frequency. This ringing frequency is applied over conductor 40 through the armature 41 and associated front contact of relay 14, conductor 42, to the input terminals of low pass filter 43 which is coupled to modulator 23 through transformer 44. Thus there is applied to channel 2 a carrier signal which is modulated by the ringing signal of voice frequency.

When it is desired to ring the trunk 1 from the line 2, there is received over the latter a similar carrier having a voice frequency ringing modulation which passes through the high pass output terminals of directional filter 26 and is applied to band-pass filter 45. Filter 45 is coupled through transformer 46 to a suitable demodulator 47 which is supplied with carrier frequency oscillations from the oscillator tube 48 which may be similar to tube 15. Therefore there exists at the coupling transformer 49, the demodulated signal representing the received ringing voice frequency. This voice frequency ringing signal is of relatively high level and is applied through low pass filter 50 and coupling transformer 51 to the receiving amplifier 52.

The output circuit of amplifier 52 is coupled through condenser 53, over conductor 54, armature 39 and associated back contact, to grid 23. In response to this voice frequency ringing signal applied to grid 28, tube 27 amplifies it and the amplified signal is applied through armature 41 and its associated back contact of relay 14, thence through rectifier 55 and a smoothing filter comprised of resistors 56, 57 and condensers 58, 59, to the grid 28. The application of this additional D. C. bias potential to grid 28 causes a proportionate increase in the D. C. plate current of tube 27 which flows through the winding of relay 4 to cause it to operate. When relay 4 operates, it connects the 20 cycle ringing current over conductors 60 through the armatures 3 and 9 and their respective front contacts to the line 1. During the transmission of intelligence signals, the hybrid coil 7 functions in the normal way to repeat the incoming intelligence from the output of the receiving amplifier 52 through windings 5 and 6, through the armatures and associated back contacts of relay 4 to the line 1. During this period the voice frequency signals which reach the grid 28 through condenser 53 are of insufficient level at the ringing frequency to convert the tube 27 from an amplifier to an oscillator generator.

While one particular embodiment has been disclosed herein, it will be understood that various changes and modifications may be made therein

without departing from the spirit and scope of the invention.

What is claimed is:

1. A two-way terminal of the character described comprising, a pair of branches for signalling in opposite directions, a carrier oscillator, a device effective in one condition to act as an amplifier and in another condition to act as an alternating current generator, means responsive to the application of a ringing signal to one end of said terminal to convert said device into a generator of alternating ringing current, and means for applying the generated currents to modulate the carrier from said oscillator and for applying the modulated carrier to the other end of said terminal.

2. A two-way terminal of the character described comprising, a pair of branches for signalling in opposite directions, a carrier oscillator, a device effective in one condition to act as a selective amplifier and in another condition to act as a generator of voice frequency ringing current, means responsive to the application of a ringing-out signal to one end of said terminal to convert said device into a generator, means for applying the generated currents to modulate the carrier from said oscillator and for applying the modulated carrier to the other end of said terminal, means responsive to the receipt of a voice frequency ringing signal to said other end of the terminal to cause said generator to produce a substantial direct current component, and means responsive to said component for applying a low frequency ringing-in current to said one end of the terminal.

3. A two-way carrier telephone terminal comprising, a transmitting branch and a receiving branch, means including a telephone line to apply a ringing control signal to one end of the terminal, means to apply a voice frequency ringing signal to the other end of the terminal, an amplifier which selectively amplifies said voice frequency signal, means responsive to said amplification to produce a corresponding direct current component, and switching means responsive to said direct current component for disconnecting the said line from said one end of the terminal and for applying a local ringing frequency to said line.

4. A two-way terminal according to claim 3 in which said amplifier is provided with circuit arrangements for converting it into an alternating current generator of voice frequency ringing current under control of the application of said ringing control signal to said one end of the terminal.

5. A two-way carrier telephone terminal comprising a transmitting branch and a receiving branch, said transmitting branch having a carrier oscillator generator, a voice frequency ringing generator of the feedback type which is normally ineffective to generate ringing currents, means responsive to control signals applied to one end of said transmitting branch to cause said generator to generate voice frequency ringing current under control of said feedback, and means to apply said voice frequency ringing current to modulate said carrier oscillator for impressing voice frequency modulated carrier on the other end of said transmitting branch.

6. A two-way carrier telephone terminal comprising a transmitting branch, a receiving branch, said transmitting branch having an associated carrier current generator, an electron tube common to both branches and normally acting as an amplifier, a feedback arrangement for said

tube, a relay for switching-in said feedback arrangement to cause said tube to generate voice frequency ringing current, means responsive to a low frequency ringing signal for controlling said relay, and means to modulate the carrier generator of the transmitting branch by said voice frequency ringing signal.

7. A two-way carrier telephone terminal comprising a transmitting branch and a receiving branch, each branch having an associated carrier current generator, an electron tube common to both branches and normally acting as an amplifier, means in said receiving branch including said associated carrier current generator to demodulate a received voice frequency ringing signal and applying it to the control grid of said electron tube whereby said voice frequency ringing signal is selectively amplified, means to rectify the amplified frequency signal in the plate current of said tube, means to apply the rectified signal to the control grid of said tube to increase the D. C. plate current, and a ringing control relay controlled by said increased D. C. plate current.

8. In a carrier telephone voice frequency ringing control system, an electron tube, a feedback arrangement for causing said tube to generate voice frequency ringing current, a relay for switching said feedback arrangement into and out of circuit with said tube, a rectifier arrangement connected in the plate circuit of said tube under

control of said relay, means controlled over a telephone line for operating said relay, means to apply the voice frequency ringing signals received over said receiving branch to the control grid of said tube to cause a marked increase in the current through said rectifier, and means to apply said low frequency ringing signal to a telephone line in response to said rectified current.

9. A voice frequency ringing current generator-discriminator for carrier telephone terminals comprising an electron tube, a feedback arrangement for said tube including a filter network sharply tuned to a voice frequency ringing signal, a rectifier arrangement connected between the plate and the control grid of said tube, a relay having contacts effective in one position to connect said rectifier arrangement in circuit with said grid and effective in another position to connect said feedback and filter in circuit, and means controlled over a telephone line for operating said relay.

10. A voice frequency ringing current generator-discriminator according to claim 9 in which said tube has its control grid connected to a telephone receiving branch whereby demodulated voice frequency ringing signal is applied to said grid, a switching relay, and a D. C. plate return circuit for said tube connected through said switching relay for applying low frequency ringing signals to said telephone line.
